United States Patent

Des. 241,695

Patented Oct. 5, 1976

241,695

SEAT

Stapleton Long, Morristown, Tenn., assignor to
The Berkline Corporation, Morristown, Tenn.

Filed Nov. 10, 1975, Ser. No. 630,321

Term of patent 7 years

Int. Cl. D6—01

U.S. Cl. D6—71

FIG. 1

FIG. 2

FIG. 3

FIG. 4

FIG. 5

FIG. 6

FIG. 1 is a front perspective view of a seat showing my design in the form of an armchair;

FIG. 2 is a side perspective view thereof;

FIG. 3 is a top perspective view thereof;

FIG. 4 is a front perspective view of a seat showing my design in the form of a sofa;

FIG. 5 is a side perspective view of the sofa of FIG. 4; and

FIG. 6 is a top perspective view of the sofa of FIG. 4. The side not shown is like the side shown, while the rear of the seat is plain and unornamented.

I claim:

The ornamental design for a seat, as shown and described.
